UNITED STATES PATENT OFFICE.

CHARLES A. BENZ AND EDWIN E. VAN CLEAVE, OF CHICAGO, ILLINOIS.

REVERSIBLE FULCRUM.

Application filed April 23, 1925. Serial No. 25,357.

The present invention relates to reversible fulcrums.

More particularly the present invention relates to a construction of reversible fulcrum including a plurality of parts which are releasably connected together and normally locked in position.

The invention has for one of its objects the provision of a reversible fulcrum construction which may be readily assembled and which may be readily locked in position.

A further object is to provide a reversible fulcrum which will be self-centering.

15 A further object is to provide a reversible fulcrum which combines ease of assembly with sturdiness.

A further object is to provide a reversible fulcrum which is well adapted to meet the 20 needs of commercial service.

Further objects will appear as the description proceeds.

Referring to the drawings—

Figure 1 is a view of part of the construction of a railway car including a reversible fulcrum embodying the principles of the present invention;

Figure 2 is a view, partly in section, taken along the plane indicated by the 30 arrows 2—2 of Figure 1;

Figure 3 is a sectional view taken along the plane indicated by the arrows 3—3 of Figure 2;

Figure 4 is a sectional view taken along the plane indicated by the arrows 4—4 of Figure 2;

Figure 5 is a sectional view taken along the plane indicated by the arrows 5—5 of Figure 2;

40 Figure 6 is a sectional view taken along the plane indicated by the arrows 6—6 of Figure 2;

Figure 7 is a view similar to Figure 6 but showing the fulcrum post turned through 45 part of a revolution to a position occupied in service;

Figure 8 is a view similar to Figure 3 but showing the parts on a larger scale; and

50 Figure 9 shows a modified form of the present invention.

The numeral 1 indicates a compression member, and the numeral 2 indicates a tension member. The numeral 3 indicates a bracket for cooperation with the fulcrum post 4. The bracket 3, though it may be secured to either the compression member 1

or the tension member 2, is shown secured to the compression member 1, the extremity of the post 4 adjacent to the tension member 2 being provided with the fork-like members 5—5 straddling said tension member 2. The post 4 is provided with the slot 6 for the reception of a brake lever (not shown) and is also provided with the aperture 7 for the reception of a pivot pin (not shown). The bracket 3 and post 4 have cooperating interfitting parts permitting relative rotation therebetween, whereby the post may be disposed in the desired angular relationship relative to the compression member 1 and tension member 2.

The bracket 3 is provided with the base portion 8 shaped to conform to the surface of the compression member 1. Said bracket 3 is provided with the conical aperture 9, 75 which aperture 9 leads to the housing 10 having the conical seat 11. The fulcrum post 4 is adapted to fit within the bracket 3 with a connection which may be termed a bayonet connection. In order to provide this bayonet connection the housing 10 of the bracket 3 has the shoulders 12—12, which shoulders 12—12 are separated by the spaces 13—13. Located within the housing 10 are the two oppositely disposed 85 abutments 14—14, which limit rotary motion of the post 4 in a manner which will be referred to hereinafter.

The post 4 is provided with the tapered end portion 15, which end portion 15 has the head 16 having the conical extremity 17 adapted to center itself upon the conical seat 11 within the housing 10 of the bracket 3. Said head 16 is provided with the two outstanding keys or lugs 18—18, which, as shown in Figure 8, have the tapered walls 19—19 adapted to cooperate with the shoulders 12—12 of the bracket 3. Said keys or lugs 18—18 are adapted to be moved into the spaces or keyways lying in rear of the shoulders 12—12.

When the fulcrum post 4 is inserted within the tapered portion 9 of the bracket 3 the outstanding keys or lugs 18—18 of said fulcrum post will, of course, be positioned to pass through the recesses 13—13 between the shoulders 12—12 of the bracket 3. When said lugs 18—18 are located within the housing 10 of the bracket 3 said post 4 will be rotated through part of a revolution. The tapered faces 19—19 of the lugs 18—18 will, by reason of their engagement with

the shoulders 12—12, force the conical extremity of the fulcrum post 4 into centering relationship with the conical seat 11 of the bracket 3. The abutments 14—14 will limit 5 rotation of the fulcrum post 4. In service a rotary movement of the fulcrum post 4 of about 40 degrees in each direction will be permitted.

According to the structure shown in Figure 9, the extremity of the post 4 bears directly against the compression member 1. Though the construction shown in said figure omits the conical seat 16 provided by the bracket 3, said construction has the advantage that the dimension of the bracket in a direction normal to the length of the compression member 1 may be less than in the structure shown in the other figures of the drawing.

20 The present invention presents the advantage that the reversible fulcrum may be readily mounted in place, and when turned to operative position will be securely locked in place by reason of the bayonet connection provided between the bracket 3 and the extremity of the fulcrum post 4.

Though certain preferred embodiments of the present invention have been described in detail, it will be clear that many modifications will occur to those skilled in the art. It is intended to cover all such modifications that fall within the scope of the appended claims.

What is claimed is:

25 1. In brake beam construction, the combination of a compression member, a tension member, a bracket secured to one of said members, and a fulcrum post positioned between said bracket and the other of said members, said bracket and said fulcrum post having cooperating keys and keyways forming a bayonet connection, said keys and keyways including tapered portions for drawing said post into said bracket and wedging said post into tight engagement with said bracket when said post is turned to move said keys into said keyways.

30 2. In brake beam construction, the combination of a compression member, a tension member, a bracket secured to one of said

members, and a fulcrum post positioned between said bracket and the other of said members, said bracket and said fulcrum post having cooperating keys and keyways forming a bayonet connection, said keys and keyways including tapered portions for drawing said post into said bracket and wedging said post into tight engagement with said bracket when said post is turned to move said keys into said keyways, said bracket and post having cooperating conical portions for centering said post in said bracket.

35 3. In brake beam construction, in combination, a bracket, a fulcrum post, said bracket and fulcrum post being provided with keys and keyways for forming a bayonet connection, said keys and keyways having tapered portions for forcing said post into said bracket when said bayonet connection is made.

40 4. In brake beam construction, in combination, a bracket, a fulcrum post, said bracket and fulcrum post being provided with keys and keyways for forming a bayonet connection, said keys and keyways having tapered portions for forcing said post into said bracket when said bayonet connection is made, said bracket and post having cooperating conical portions adapted to center said post relative to said bracket when 45 said post is drawn into said bracket.

45 5. In brake beam construction, in combination, a fulcrum post, a bracket for receiving one end of said post, and supporting members for said bracket and post, said bracket and post having interfitting keys and keyways forming a bayonet connection, said bracket and post having cooperating tapered portions and having conical bearing surfaces, said tapered portions and conical bearing surfaces being so positioned that engagement between said tapered portions forming the said bayonet connection will force said conical surfaces into bearing engagement.

90 Signed at Chicago, Illinois, this 21st day of April, 1925.

CHARLES A. BENZ.
EDWIN E. VAN CLEAVE.
